UNITED STATES PATENT OFFICE.

WALTER A. HEINRICH, OF ST. LOUIS, MISSOURI, ASSIGNOR, BY MESNE ASSIGNMENTS,
TO W. N. MATTHEWS CORPORATION, OF ST. LOUIS, MISSOURI, A CORPORATION OF
MISSOURI.

SWITCH BOX AND SWITCH CARTRIDGE.

Application filed February 16, 1922. Serial No. 536,847.

To all whom it may concern:

Be it known that I, WALTER A. HEINRICH, a citizen of the United States, residing at St. Louis, Missouri, have invented a certain new and useful Improvement in Switch Boxes and Switch Cartridges, of which the following is a full, clear, and exact description, such as will enable others skilled in the art to which it appertains to make and use the same, reference being had to the accompanying drawings, forming part of this application.

My invention relates to electrical distribution apparatus and particularly to fuse switches and their containing boxes such as are used in high potential transmission lines. The general types of switch box involved is shown in prior patents, No. 1,288,951 and No. 1,398,335, issued to Claude L. Matthews and myself, December 24, 1918, and November 29, 1921, respectively.

The present invention comprises improvements upon the box and switch cartridge illustrated in these patents whereby I am enabled to more surely protect the person who operates the switch cartridge and to positively prevent destruction of the cartridge or the box due to the blowing of a fuse.

In the accompanying drawings which illustrate a selected embodiment of my invention—

Figure 1 is a section through my switch box showing a switch cartridge in closed position, in full lines, and in open position, in dotted lines.

Figure 2 is a front view of the box with its door removed.

Figure 3 is a bottom view of the box.

Figure 4 is a vertical section through the switch cartridge.

Figure 5 is a bottom view thereof.

Figure 6 is a transverse section through one of the cartridge contact elements and is taken on line 6—6 of Figure 1.

Figure 7 is a section similar to Figure 4 but showing a more economical form of the switch cartridge.

The fuse box has a bottom 1, a back 2, sides 3 and 3^a, a top 4, and a door 5 comprising a wall opposite to the back 2. Insulators 6 and 7 are mounted upon back 2 of the box and respectively support the line terminals. Side 3 is provided with an

opening adjacent to the upper terminal in 55 which is placed an insulator 6^a through which the lead-in wire passes and side 3^a is provided with an opening adjacent to the lower terminal in which an insulator 8 is located through which the lead-out wire 60 passes. The bottom 1 of the box is provided with an opening 9 extending through the edge of the bottom facing door 5.

The switch cartridge, best illustrated in Figure 4, preferably comprises a main tube 65 10 of insulating material which carries terminal engaging elements 11 and 12 of conductive material. Tube 10 is led into the bottom of element 11 and preferably provided with a threaded engagement therewith. The lower portion of element 11 is split at 13 and the split portion is provided with a screw 14; this construction providing a clamp for positively engaging tube 10 and eliminating a set screw engagement such as has been used previously and which was objectionable because of the fact that the set screw might project through the wall of the tube and provide a leakage 80 from the interior of the tube to the interior of the switch box. The upper face of element 11 is recessed at 15, the bottom wall 16 of the recess is perforated at 17, and a plug 18 is screwed into recess 15. Recess 15 and plug 18 are adapted to receive one 85 end of a fuse wire 19 and clamp the same securely in contact with the conductive element 11.

Tube 10 passes entirely through element 12 and extends beyond same through the opening 9 in bottom 1 of the box. Element 12 is split at 20 and provided with a screw 21 to form a tube clamping arrangement similar to that described for element 11. The portion of element 12 opposite to the 95 terminal engaging blade is recessed on its lower side to admit a second insulating tube 22 and is recessed upon its upper side to provide a fuse engaging shelf and for a clamping screw 23 corresponding to the 100 similar construction in the upper end of element 11.

Tube 22 extends downwardly from this portion of element 12 through the opening 9 in the bottom 1 of the box and terminates 105 adjacent to the end of tube 10. A block 24 of insulating material unites tubes 10 and 22 at their bottom but is open on the

lower side to leave the lower ends of the tubes open to the atmosphere.

To form the fuse 19 I double a piece of fuse wire upon itself, twisting the doubled portions together and leaving one end 25 extending a substantial distance beyond the other end. This projecting end is clamped in position in recess 15 and provides a portion of the fuse of reduced area, the object 10 of which will be apparent to those skilled in the art.

It will be noted that the fuse wire extending from its contact with element 12 at 26 to its contact with element 11 at 25 passes 15 outside of the switch box. Furthermore, an abrupt return bend is formed in wire 19 in this portion which is projecting beyond the bottom of the box. This arrangement provides an efficient switch cartridge and box 20 construction in which the blowing of the fuse cannot result in the destruction of the switch parts due to the filling of the box with metallic vapor and the resulting conflagration.

25 If the fuse is blown, it will be at its weakest portion which is in the tube recess of element 11. The resulting arc is lengthened downwardly as the fuse wire melts until the abrupt bend 27 is reached. This 30 hairpin turn in the path will destroy the arc and terminate its capacity for damage.

The bottom 1 of the box is provided with hinge butts 28 and block 24 is provided with hinge members 29 adapted to pivot in butts 35 28.

The ends of these hinge members 29 have integral eccentrics 30 so shaped that when the cartridge is in the vertical full line 40 position of Figure 1, the hinge members 29 cannot be disassembled from hinge butts but when the cartridge is swung to the dotted line position, the hinge members may be raised and slidably disengaged from the hinge butts. Due to this construction, it is 45 unnecessary for an operator to ever put his hand inside of the box. If a cartridge has been removed and is being replaced, the lower end is slidably engaged with the hinge butts on the bottom of the box, as indicated by the dotted line position of the 50 cartridge in Figure 1, and the operator may swing the cartridge into the vertical switch-closing position by means of a short stick.

Member 11 is provided with an eye 31 so that when it is necessary to remove the 55 switch cartridge, the hook on a stick may be used to engage eye 31 to pull the cartridge into the switch-opening dotted line position in which it may be safely grasped by the operator.

60 In the construction shown in Figure 7, the shorter tube 32 is inclined toward the longer tube 33. The contacting portions of the tubes are cut away at 34 to accommodate the fuse wire. The hinge in this construction is simpler than the one described above,

a pin 35 being mounted across the recess in the box bottom and a suitable hook 36 being provided on the cartridge. This construction is simpler than that previously described but does not vary therefrom in principle or operation as it retains all the arc destroying features hereinbefore mentioned.

Various modifications suggest themselves in the construction of this device and I desire to include all of such as fall within the 75 scope of the following claims.

What I claim is:

1. In a switch box, spaced line terminals, spaced terminal engaging elements, and a fuse having a reduced sectional area near one end and secured near its respective ends to said elements and projecting, between its ends, from said box.

2. In a switch box, a wall having an opening, line terminals mounted in said box, terminal engaging elements, respective insulating tubes secured to said elements and leading from the latter through said opening, and a fuse wire extending through said tubes, connecting said elements and wholly enclosed by said tubes and by portions of said engaging elements while inside the box.

3. In a switch box, spaced line terminals, spaced terminal engaging elements, and a fuse secured near its respective ends to said elements and projecting, between its ends, from said box, and an insulator tube which with said elements surrounds all that portion of said fuse which is located within the box.

4. In a switch box, spaced line terminals, spaced terminal engaging elements, and a fuse secured near its respective ends to said elements and projecting, between its ends, from said box, the projecting portion including an abrupt bend, and a tubular insulator enclosing said fuse from element to element and provided with a lateral opening to receive the bent portion of said fuse.

5. In a switch box, line terminals, a box wall having an opening extending to an edge of said wall, a doorway in the side of the box facing this wall edge, a fuse container having terminal engaging elements and hinged on said wall between the sides of said opening and swingable through said doorway into terminal engaging position.

6. In a switch box, line terminals, a box wall having an opening extending to an edge of said wall, a doorway in the side of the box facing this wall edge, a hinge element mounted on said wall between the sides of said opening, a fuse container provided with terminal engaging elements and having a hinge member slidably engageable and disengageable with said element when said container is outside of said box, said container being swingable on said hinge element through said doorway into position to engage said terminals with said elements.

7. In a switch cartridge, spaced terminal engaging elements, and a hairpin shaped fuse secured near its respective ends to said elements and having its legs surrounded throughout their length by insulating material but being open to the atmosphere adjacent the outside of its bent portion.
8. A switch cartridge comprising spaced terminal engaging elements, a fuse secured at one end to one of said elements, extending therefrom past the other of said elements, provided with a return bend beyond the latter element and having its other end secured to the latter of said elements, an insulating tube extending from the first of said elements to the bend and enclosing the corresponding portion of said fuse, an insulating tube extending from the second of said elements to the bend and enclosing the corresponding portion of said fuse.
9. A switch cartridge comprising spaced terminal engaging elements, a fuse secured at one end to one of said elements extending therefrom past the other of said elements, provided with a return bend beyond the latter element, and having its other end secured to the latter of said elements, an insulating tube extending from the first of said elements to the bend and enclosing the corresponding portion of said fuse, an insulating tube extending from the second of said elements to the bend and enclosing the corresponding portion of said fuse, said tubes being united so as to form a barrier of insulating material between said elements and the bend in said fuse.
10. In a switch cartridge, a terminal engaging element provided with a recess, an insulating tube leading from said recess, a second terminal engaging element provided with a recess, an insulating tube leading from the latter recess, said tubes being of different lengths but terminating adjacent to each other, a fuse wire secured at its opposite ends in said elements, respectively,
- and extending within said elements intermediate its ends and having its end, which is secured to the element farthest from the ends of said tubes, of reduced area.
11. In a switch cartridge, aligned terminal engaging elements each having a recess provided with a perforated transverse partition wall, an insulating tube on one side of said wall leading away from each recess with an open end aligned with the perforation in said wall, a fuse wire entering the recesses through said tubes, and means for clamping the terminals of said wire against the faces of said recess on the opposite sides of said walls.
12. A switch cartridge comprising inclined insulating tubes contacting with each other at one end of each and terminating near their point of contact, one tube being longer than the other, individual terminal engaging elements at the separated ends of said tubes, and a fuse wire connected at its opposite ends to said elements respectively and extending through said tubes intermediate its ends.
13. A switch cartridge comprising spaced terminal engaging elements, a fuse secured at one end to one of said elements, extending therefrom past the other of said elements, provided with a return bend beyond the latter element and having its other end secured to the latter of said elements, an insulating tube extending from the first of said elements to the bend and enclosing the corresponding portion of said fuse, an insulating tube extending from the second of said elements to the bend and enclosing the corresponding portion of said fuse, the bent portion of the fuse being open to the atmosphere.
- In testimony whereof I hereunto affix my signature this 11th day of February, 1922.

WALTER A. HEINRICH.
